DESIGN FOR A BOILER

Paul W. Vandenberg, Elmhurst, and Edward W. Enthof, Chicago, Ill., assignors to Crane Co., Chicago, Ill., a corporation of Illinois

Application August 9, 1939, Serial No. 86,560

Term of patent 7 years

To all whom it may concern:

Be it known that we, Paul W. Vandenberg and Edward W. Enthof, citizens of the United States, the said Vandenberg residing at 373 Elm Avenue, in the county of Du Page, city of Elmhurst, State of Illinois; and the said Enthof residing at 1639 West 21st Place, in the county of Cook, city of Chicago, State of Illinois, have invented a new, original, and ornamental Design for a Boiler, of which the following is a speci-

fication, reference being had to the accompanying drawing, forming part thereof.

The figure illustrates a perspective view of a boiler embodying our design. The sides not shown are substantially plain.

We claim:

The ornamental design for a boiler, substantially as shown and described.

PAUL W. VANDENBERG.
EDWARD W. ENTHOF.
